UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

STEREOTYPE PRINTING-PLATE.

1,150,474.

Specification of Letters Patent. Patented Aug. 17, 1915.

Original application filed August 9, 1906, Serial No. 329,833. Divided and this application filed October 24, 1913. Serial No. 796,998.

To all whom it may concern:

Be it known that I, HENRY A. WISE WOOD, a citizen of the United States, residing at New York, in the county of New York and 5 State of New York, have invented a new and useful Stereotype Printing-Plate, of which the following is a specification.

This invention relates to a curved stereotype printing plate.

10 The principal object of the invention is to provide a plate of this character especially adapted for being operated upon by gravity shaving means such, for example as those shown in my applications for Letters-Patent of the United States No. 310,343 and No. 15 329,833, filed respectively April 6th and August 9th, 1906, of the latter of which this is a division.

Reference is to be had to the accompanying drawings in which—

Figure 1 is a plan of a portion of a machine on which plates constructed in accordance with this invention can be finished and cooled. Fig. 2 is a transverse sectional view 25 of the same on the line 2—2 of Fig. 1. Fig. 3 is a sectional view on the line 3—3 of Fig. 1. Fig. 4 is a sectional view on the line 4—4 of Fig. 1, and Fig. 5 is a longitudinal sectional view of the plate itself.

30 The plate *g* is shown as being supported on a plate finishing machine comprising a frame having an inclined body or runway *a'* for carrying the plates. The plates are intended to move by gravity down the runway supported by a series of rollers 20. They are controlled as described in the second one of my above mentioned applications by a reciprocating bar or gate 21 arranged 35 across the table *a'*. The operation of this

40 need not be described but it is sufficient to say that it is provided with stops 24 thereon adapted to come in front of the edges of the plate *g* and stop it in one position of the stop. The stop is then moved

45 by a cam 27 to bring the stops 24 out of alignment with the edges of the plate and allow the plate to move down the incline supported as it is on the rollers 20. While 50 passing down the incline the bottom edges of the plate are trimmed off by rotary saws *b* as shown in Fig. 3. This provides the straight edges of the plate with a double bevel *g'* so that it can rest on the rollers 20 above the finishing arch and also on the

rollers 20^a in the shaving arch as shown in Fig. 4 without marring the edges of the plate. For the purpose of constructing the plate to coöperate perfectly with this machine it is provided with a smooth surface 29 along the two inner longitudinal edges. 60 This surface is made smooth by stopping the circumferential ribs 30 at a short distance from these edges. This serves two purposes. First, it permits the plate to be guided by the rollers 20 without injuring 65 the outer or type surface; and second, it allows the operation of the gate 21 to prevent the entrance of the plate *g* out of time. This gate is operated to open so as just to let the front end of a plate by. The gate immediately thereafter is thrown against the inner surface of the edge of the plate on one side by its spring 23. Thus, immediately 70 the plate passes the gate, the latter snaps closed behind it. This causes the gate to be 75 opened only at the correct moment so that no plate put in late can get half out of time. The gate is opened for an instant and if no plate is there it closes, but if a plate has been in position and starts to pass on down 80 the incline, the gate is held open by coming against the smooth inner edge 29 of one side of the plate and when the plate passes it, it snaps closed behind it.

It is to be understood also that the right 85 hand gate in Fig. 2 is clear of the plate or type surface while the left side gate is bearing against the inner side of the plate. This prevents the rubbing of the type. This gate is shown at the entrance for admitting 90 the plate to the trimming saws *b* and it is to be understood that the plate continues after it has been trimmed by these saws to pass over the same kind of rollers. The saws trim the plate on its outer edge and also cut 95 off the sharp inner edge which is usually left on the plate. Thus the plate is left with double beveled longitudinal edges *g'*.

The rolls 20^a inside the shaving arch on which the plate is supported when being 100 shaved are shown as simple cones unlike the rolls 20. They support the outer inclined bevel of the plate and as the plate, while in the arch, is cooled only in the outer surface, it will not contract inwardly to 105 dislodge it from these rolls.

Although I have illustrated and described only a single form of the invention I am

aware of the fact that modifications can be made therein by any person skilled in the art without departing from the scope of the invention as expressed in the claims, therefore, I do not wish to be limited to all the details of construction herein shown and described, but—

What I do claim is:—

10. A curved stereotype plate having inner circumferential ribs extending to within a short distance of the straight edges of the plate, thereby leaving smooth inner surfaces adjacent to said edges.
15. A curved stereotype plate having a smooth inner surface adjacent to a straight

edge thereof, said straight edge being double beveled.

3. A curved stereotype plate provided with double beveled straight edges whereby it can rest on grooved rollers in a gravity 20 shaving machine without injury to the type surface.

In testimony whereof I have hereunto set my hand, in the presence of two subscribing witnesses.

HENRY A. WISE WOOD.
